UNITED STATES PATENT OFFICE.

JONAS M. MILLER, OF PLAIN CITY, OHIO.

TELEGRAPH TRANSMITTER.

Application filed October 22, 1925. Serial No. 64,167.

This invention relates to improvements in telegraph transmitters and particularly to the construction of a transmitting machine provided with a key board with the characters on the keys arranged in any predetermined manner to permit of the convenient operation thereof in the transmission of signals.

An object of the invention resides in providing a telegraph transmitter having a housing in which is mounted a transmitting mechanism composed of a plurality of independently operated disk members adapted to step by step movement and in said movement to send a signal impulse by telegraph, a suitable keyboard mechanism comprising a plurality of independently operable keys similar to the keys of the typewriter being provided for moving the disk independently through a separate movement upon depression of the keys in order to send a signal indicating a predetermined character by telegraph.

A further object of the invention includes the provision of a telegraphic transmitter by which code signals may be sent by telegraph through the operation of suitable keys forming a keyboard of the instrument so that it is not necessary for the operator to be familiar with code transmission in order to send a message, and in addition signals may be sent more rapidly and uniformly than by the manual operation of a spinning key.

The invention comprehends numerous other objects and improvements residing in the details of construction and the relation of the parts which are more particularly pointed out in the following detailed description directed to a preferred form of construction, it being understood, however, that various changes may be made in the size, shape and arrangement of the parts for carrying out the invention, without departing from the spirit or scope of the same as herein set forth.

In the drawings forming part of this application:

Figure 1 is a side elevation of the improved transmitter construction forming the subject matter of this invention showing portions broken away and in section.

Fig. 2 is a plan view of the improved transmitter showing portions broken away and in section.

Fig. 3 is a detail perspective view of one of the circuit makers carried by the disk members operable for sending signal impulses in the rotation of the disk member.

Fig. 4 is a diagrammatic view illustrating a complete telegraph circuit in the manner in which the disk member operated through one step of movement cooperates with a stationary member for sending a code signal operating a receiving instrument in accordance therewith.

A housing is indicated at 1 which is provided with a plurality of successively stepped portions as indicated at 2 associated with each stepped portion are a row of keys 3. This construction of the housing and the mounting of the keys places the keys in stepped relation as illustrated in the plane view in Fig. 2 similar to the keyboard of the typewriter, and the keys are each provided with a symbol indicating the character which will be transmitted by close signal over the telegraph line controlled by the instrument upon the operation of the key.

A plurality of shafts 4 mounted in spaced relation and extending from end to end of the housing serve to pivotally mount the keys 3 of the various rows, one row being mounted on the shaft 4, which shaft also forms a common circuit to all of the disk members 5 mounted thereon, there being one disk member for each key 3. A plurality of horizontal partition walls 6 are mounted in the housing in a predetermined spaced relation under each of the shafts 4 and on each of these partition walls within the plane of the disk 5 are mounted a plurality of supporting plates 7 of suitable insulating material. These plates are also secured to the inside walls of the housing. All of the plates 7 are formed with substantially semi-circular recesses 8 which lie in concentric relation with the periphery of the disk 5, and in the central portion are adapted to receive and support the contact members 9, which are provided with common circuit connection through the rod members 10 extending from end to end in the housing and in spaced parallel relation to respective shafts 4 of the row of disks with which they are associated.

A plurality of curved or arcuate contact springs 11 are mounted on the periphery of the disks 5 in equal spaced relation and intermediate the mounting for the contact

springs 11 the periphery of the disk is formed with notches 12 in which the pawls 13 carried on the under side of each key 3 is adapted to seat so that in the depression of each key 3, the disk 5 associated therewith will be rotated one step which will move one of the contact springs 11 over the stationary contact spring 9 of one end to the other thereof for making the circuit control by said contact and contact spring.

A tension spring 14 secured to each of the levers 3 is anchored at its opposite end in a suitable manner to the casing for normally retaining the keys 3 in the raised position as shown in Fig. 1, the movement of which keys are limited by the ends of the front 15 in the stepped front wall portion of the casting 1. The lower end of the slot limits the downward movement of the keys or levers 3 so that the operation of the lever or keys from one end of the slot to the other forms one step of movement for the disk 5 in order to produce an operation for sending in code the signal impulse for a certain character. The reverse rotation of the disk 5 is prevented through the cooperation of the contact springs 11 with the surface 8 of the insulating plate members 7.

The stationary contact plates 9 are formed with recesses 16 in the contact face thereof adapted to cooperate with the contact springs 11 so as to divide the contact face into a plurality of projections of varying lengths for representing dots and dashes of the telegraph code. It will thus be appreciated that the operation of one of the disks 5 through one step of movement will move one of the contact springs 11 over all of the contact portions of the stationary contact plates 9 associated therewith and thus send a series of dots and dashes over the telegraph line representing the code signal for the character of the key depressed for operating the relay 17 illustrated in the diagrammatic view in Fig. 4 in accordance with the impulses sent over the line 18.

The sounder or relay 17 may be replaced by any other suitable mechanism such as is at present used in the art for receiving and recording messages in a well known manner.

With a transmitter of this character, it will be seen that inexperienced operators who may be familiar with the key-board are

able to send a telegraphed message in a quick and efficient manner which will operate a suitable reproducing or recording mechanism at a receiving station where the message is recorded. As shown in Fig. 1, the rods 10 are all connected at one side of the circuit, while the shafts 4 are connected in the opposite side of the circuit so that the disk 5 and co-related stationary contact members independently control energization of the circuit in the operation of the recording mechanism therein.

Having thus described my invention, what I claim as new is:

A telegraph transmitter, comprising a housing having a stepped front wall portion, a plurality of shafts mounted in predetermined relation in the end walls of said housing, a plurality of groups of lever keys pivotally mounted at one end in spaced relation on said shafts and projecting through slots formed in the stepped front wall of said housing adapted to limit the operation thereof, said lever keys being independently operable, means for normally holding said lever keys in a predetermined position, a plurality of disk members mounted on said shafts for relatively independent rotation, one of said disk members being associated with each lever key, ratchet means carried by each lever key for engagement with its respective disk members for rotating said disk member in a step of movement in one operation of the key, a plurality of insulating plates mounted in predetermined relation in said housing and corresponding in number to said disk members, stationary contact plates mounted on said insulating plate members, said stationary contact plates being formed in a predetermined manner to represent code signals of predetermined characters, and contact springs mounted on said disk members in a predetermined manner for engagement with said stationary plate members and operable in one step of movement to engage all of the contact portions of said stationary plate members for energizing a telegraph circuit in a predetermined manner to send the code signal for the character represented thereby.

In testimony whereof I affix my signature.

JONAS M. MILLER.
